LEO ROSEMAN, OF NEWARK, NEW JERSEY

FASTENER TAPE

Application filed May 5, 1930. Serial No. 449,751.

This invention relates in general to fastener tape including a strip of fabric on which are secured hooks or eyes, generally used with garments, one object of the invention being to provide such fastener tape embodying a novel and improved construction wherein greater strength shall be attained with the same amount of fabric and stitching used in known fastener tape.

Another object is to provide fastener tape of this character comprising a single strip of fabric folded longitudinally to form two overlapping flaps at least one of which is formed of a plurality of thicknesses or plies, one inner one of which plies has slits or openings into which are inserted the engaging portions of the hooks or eyes, as the case may be, so that the bases of the hooks on the eyes are located between two plies and the bills of the hooks or the loops of the eyes project beyond the edge of the corresponding flap, so that the fastener elements, i. e. hooks or eyes, cannot be displaced from the slits except by unfolding the strip, whereby the tape including the fastener elements can be handled or sold without sewing of the fastener elements into the tape and then sewed as the tape is applied to a garment, or at any time, or the fastener elements can be sewed into the tape as a step in the manufacture thereof.

Another object is to provide such fastener tape wherein said slits or openings for the fastener elements are arranged so that they are covered or made invisible when the flaps are sewed together.

Other objects are to provide fastener tape of the character described embodying novel and improved features of construction wherein the stitches for securing the fastener elements upon the fabric are rendered invisible; to provide such fastener tape wherein the attachment of the fastener elements to the fabric is of maximum strength and reinforced by direct contact of the bases of said elements with the fabric at opposite sides of said slits; to provide fastener tape of this character in which the fastener elements can be arranged in either flap of the strip; and to obtain other advantages and results as

will be brought out by the following description.

Referring to the accompanying drawings in which corresponding and like parts are designated throughout the several views by the same reference character,

Figure 1 is a top plan view of a piece of eye fastener tape embodying my invention with one of the flaps turned up for clearness in illustration, and before the tape is stitched.

Figure 2 is a top plan view of the tape shown in Figure 1 after stitching.

Figure 3 is a transverse vertical sectional view on the line 3—3 of Figure 2.

Figure 4 is a view similar to Figure 1 showing a modified form of the invention.

Figure 5 is a top plan view, with portions broken away, of another modification of the invention.

Figure 6 is a transverse vertical sectional view on the line 6—6 of Figure 5.

Figure 7 is a top plan view of a portion of hook fastener tape embodying the invention, and

Figure 8 is a transverse sectional view on the line 8—8 of Figure 7.

Specifically describing the embodiment of the invention illustrated in Figures 1 to 3 of the drawings, the fastener tape includes a strip 1 of suitable fabric which is folded longitudinally at 2 to form two overlapping flaps 3 and 4. As shown on the drawings, each of these flaps consists of two plies of the fabric which are formed by turning the edge portions of the flaps under or inward. The turned under portion of the flap 3 is designated 5, while the turned under or inner portion of the flap 4 is designated 6, and these turned under portions are arranged in direct contact with each other.

For convenience in description, the flap 3 will be called the top flap, while the flap 4 will be referred to as the bottom flap.

The top flap 3 has a plurality of slits 7 to receive fastener elements formed in the turned under or inner ply 5, and preferably these slits are disposed between the exposed edge 8 of the flap and the longitudinal fold 2, so that when the flaps 3 and 4 are arranged

in contacting and overlapping relation, the slits 7 are covered or invisible.

Each of a plurality of fastener elements 9, for example eyes, has its base portion 10 arranged between the plies of the top flap 3 and its engaging portion or loop 11 passing through one of the slits 7 and extending beyond the exposed edge 8 of the top flap. Preferably the distance between the slits 7 and the longitudinal fold 2 is less than the length of the fastener elements, so that the fastener elements cannot be displaced from the slits while the strip is folded, it being possible to remove the fastener elements only by turning back one of the flaps.

The fastener tape may be sold, handled or transported in the condition above described and as shown in Figure 1 of the drawings, without stitching, and the flaps 3 and 4 may be stitched together at any time, for example, when the tape is applied to a garment, and this stitching may or may not be utilized to reinforce the attachment of the fastener elements to the tape. It will be observed that the fastener elements will be prevented from pulling out of the tape when the flaps are stitched together, by contact of the base portions 10 with the fabric at opposite sides of the slits 7 and by the complete enclosing of the base portions between the plies of the flap.

In many instances, it will be desirable to stitch the flaps together as a step in the manufacture of the tape, for example, as shown in Figure 2 of the drawings, where a line of stitching 12 extends longitudinally of the strip and through both flaps so as to connect the flaps together. Also, preferably, this line of stitching is disposed between the slits 7 and the exposed edge 8 of the top flap, and stitching may include lateral stitches 13 passing over or encircling the base portions 10.

The fastener elements may be inserted in the lower flap 4 instead of the upper flap, if desired, for example, as shown in Figure 4 of the drawings. Here the turned in or inner ply 6 is provided with a plurality of slits 14 through each of which passes the engaging portion 11 of a fastener element, the base portion 10 of which is disposed between the plies of the flap 4. The slits 14 are so arranged as to be covered by the top flap 3 when the flaps are arranged in contacting and overlapping relation. This form of fastener tape may or may not be stitched in the same manner as the tape shown in Figures 1 to 3 inclusive.

In some instances it may be desirable to form the tape so as to cover the stitches which secure the flaps together, and for this purpose the construction shown in Figures 5 and 6 may be provided. In this form of the invention, the top flap 15 corresponding to the flap 3 of the construction shown in Fig-

ures 1 to 2 is initially made wider than the flap 3 and the portion constituting the extra width may be returned upon the flap as at 16 after the line of stitching 17 corresponding to the stitches 12 of Figure 2 has been formed. In this type of fastener tape, the slits 18 to receive the fastener elements are disposed adjacent the exposed edge of the flap formed by the fold resulting from turning back the portion 16. The turned back portion 16 may also serve as a garment attaching flap and the edge of a garment A may be stitched between the turned back portion 6 and the body of the flap 15 as by a line of stitching 19.

Obviously the invention may be utilized in hook fastener tape as well as in eye fastener tape, for example as shown in Figures 7 and 8 of the drawings. The strip of fabric is folded exactly as in the case of the eye fastener tape, and the slits 7 for receiving the fastener elements are disposed in the same manner in the flaps. The base portions 20 of the hooks are arranged between the plies of the flaps, as are the base portions 10 of the eyes, while the bills 21 of the hooks pass through the slits 7 and overlie the top flap 3 as clearly shown in the drawings. The hook fastener elements may or may not be stitched to the strip, as desired; but when they are secured to the strip by stitching, I may utilize a line 23 of stitches running longitudinally of the strip which includes lateral stitches 24 encircling the base portions 20 of the hooks.

It will be understood by those skilled in the art that the flaps of the strip may be formed with more or less plies or thicknesses of material, and only one of the flaps, that is the flap carrying the fastener elements, need have more than one ply.

It will be observed that the invention enables a tape of great strength to be obtained with a relatively small amount of material, and with no more stitching than is commonly used in fastener tape of the same general character. The engagement of the base portions of the fastener elements with the material in the sides of the slits, greatly reinforces the attachment of the fastener element to the strip. Furthermore, the arrangement of the slits and the stitching prevents ravelling or distortion of the fabric at the edges of the slits.

As shown in the drawings, the fastener elements, i. e., the hooks and eyes, are made of wire, and the base portions thereof are formed of loops of a certain shape; but while these are the now preferred forms of the fastener elements, other suitable types of fastener elements may be utilized.

While I have shown and described the invention as embodied in certain details of construction, it will be understood that this is primarily for the purpose of illustrating

the principles of the invention and that many modifications and changes may be made in the details of the fastener strip, in the form of the fastener elements and in the manner of attaching the fastener elements to the strip, without departing from the spirit or scope of the invention. Therefore, I do not desire to be understood as limiting myself except as required by the following 10 claims when construed in the light of the prior art.

Having thus described my invention, what I claim is:

1. Fastener tape comprising a single strip 15 of fabric folded longitudinally to form two overlapping flaps, the edge portion of one of said flaps being turned under to form two plies, said turned under portion having slits disposed between the fold formed by said 20 turned under edge portion and the edge thereof to receive fastener elements, and fastener elements each having a base arranged between two of said plies and an engaging portion projecting through one of said slits and exposed.

2. Fastener tape comprising a single strip of fabric folded longitudinally to form two overlapping flaps one of which has a plurality of plies including an outer ply and 30 an inner ply, the inner ply having slits to receive fastener elements, and fastener elements each having a base arranged between two of said plies and an engaging portion projecting through one of said slits beyond 35 the exposed edge of the corresponding flap, said slits being disposed between the exposed edge of the flap and said longitudinal fold so as to be covered or concealed by the flap.

3. Fastener tape comprising a single strip 40 of fabric folded longitudinally to form two overlapping flaps one of which has a plurality of plies, one of the inner plies having slits therethrough to receive the engaging portions of fastener elements, and fastener 45 elements each having a base arranged between two of said plies and an engaging portion projecting through one of said slits and exposed, said slits being covered or concealed by the overlapping portions of the flaps.

50 4. Fastener tape comprising a single strip of fabric folded longitudinally to form two overlapping flaps one of which has a plurality of plies including an outer ply and an inner ply, the inner ply having slits therethrough to receive the engaging portions of fastener elements, and fastener elements each having a base arranged between two of said 55 plies and an engaging portion projecting through one of said slits and beyond the exposed edge of the corresponding flap, said slits being disposed between said exposed edge of said flap and said longitudinal fold.

5. Fastener tape comprising a single strip 60 of fabric folded longitudinally to form two overlapping flaps one of which has a plu-

rality of plies including an outer ply and an inner ply, the inner ply having slits therethrough to receive the engaging portions of fastener elements, and fastener elements each having a base arranged between two of said plies and an engaging portion projecting through one of said slits and lying exposed upon the adjacent side of the other flap for engagement with complemental fastener elements.

6. Fastener tape comprising a single strip of fabric folded longitudinally to form two overlapping flaps the edge portion of one of said flaps being turned under to form two plies, said turned under portion having slits therethrough to receive the engaging portions of fastener elements, and a fastener element having a base arranged between said two plies and an engaging portion projecting through one of said slits and lying exposed upon the adjacent side of the other flap for engagement with complemental fastener elements.

7. Fastener tape comprising a single strip of fabric folded longitudinally to form two overlapping flaps, the edge portion of one of said flaps being turned under to form two plies, said turned under portion having slits therethrough to receive the engaging portions of fastener elements, and fastener elements each having a base arranged between said two plies and an engaging portion projecting through one of said slits, the edge portion of the other flap being turned in and overlapped by the first-mentioned flap and said 95 engaging portions of said fastener elements lying exposed upon the adjacent side of said turned in portion of the second-mentioned flap.

8. The fastener tape set forth in claim 5, 105 with the addition of a line of stitching extending longitudinally of said flaps and connecting them between said slits and the exposed portions of said elements.

9. The fastener tape set forth in claim 6, 110 with the addition of a line of stitching extending longitudinally of said flaps and connecting them between said slits and the exposed portions of said fastener elements.

10. The fastener tape set forth in claim 5, 115 with the addition of a line of stitching extending longitudinally of said flaps and connecting them between said slits and the exposed portions of said elements, and wherein said first-mentioned flap is folded outwardly upon itself to cover or conceal said stitches and provide a garment attaching flap.

LEO ROSEMAN.
